MECHANICAL PENCIL

Fred P. Moore, Chicago, Ill., assignor to Ever-sharp, Inc., Chicago, Ill., a corporation of Delaware

Application May 25, 1942, Serial No. 444,332

19 Claims. (Cl. 120—17)

This invention relates to mechanical pencils of the step-by-step type wherein lead sticks are fed successively from the magazine by reciprocating action of the lead feeding mechanism.

The invention has for one of its general objects the simplification and reduction in cost of manufacture of such pencils, and for a particular object the provision of a construction which eliminates the inaccuracies and uncertainties resulting from necessary tolerance variations of various parts of the mechanism, and hence provides a pencil having the desired certainty and accuracy in the lead feeding operations.

Other and further objects of the invention will be pointed out or indicated hereinafter or will be apparent to one skilled in the art upon an understanding of it or use of it in practice.

For the purpose of explaining the nature of the invention, I show in the accompanying drawing, and hereinafter describe, one form in which it may be embodied. It is to be understood, however, that this is presented merely by way of illustration, and hence is not to be construed in any fashion for the purpose of limiting the appended claims short of the true and most comprehensive scope of the invention in the art.

In said drawing,

Fig. 1 is a side view, partly in section, of a pencil mechanism embodying the invention;

Fig. 2 is a showing in perspective of various parts of said mechanism disassembled;

Fig. 3 is an elevational view of one of the stave members forming a part of said mechanism;

Fig. 4 is a lateral view of such stave member, showing only its upper and lower portions, on a scale considerably larger than that of Fig. 2;

Fig. 5 is a longitudinal sectional view illustrating a pencil with the mechanism of Fig. 1 embodied therein, same being on a considerably larger scale than Fig. 1 and being shortened by the breaking out of a portion of the device;

Fig. 6 is a cross section on line 6—6 of Fig. 1 but on a larger scale; and

Fig. 7 is a cross section on line 7—7 of Fig. 1 but on a larger scale.

In the manufacture of mechanical pencils of the type wherein lead sticks are fed successively from a magazine to the writing point in a step-by-step manner, it has been the practice to form the magazine of tubular stock and to form the lead gripping members separately from the magazine and connect the various separately formed parts to one another in a general end-to-end relationship. Because of the fact that in quantity

production various tolerances have to be allowed in the size of the various individually formed parts, it has been an undesirably frequent occurrence that, due to the tolerance variations in the different parts, the assembled device is not properly or accurately operative. Such instances may occur, for example, when the lengths of various individual parts assembled in a given pencil are at the minimum tolerance limit or when the lengths of the various parts assembled in a given pencil are at the maximum tolerance limit. The present invention eliminates such difficulties and thereby greatly reduces the number of rejects and, moreover, greatly simplifies the manufacture and produces a more accurate, desirable and economical device.

The nature of the invention will be ascertained most quickly from a description of the illustrative embodiments shown in the drawing, which is as follows.

To form the magazine and the lead gripping members, I provide a plurality of complementary stave-like members of the form illustrated in Figs. 3 and 4. These may be formed of suitable sheet metal by die press operations. Each of these staves is shaped with a transversely arched magazine portion 10 which, as in the instance where three stave members are employed to form the magazine, as herein illustrated, forms an arc or segment having an extent of 120 degrees. At the upper end of the stave member, marginal parts of the magazine portion are flanged inwardly as shown at 11 in Fig. 6. At its lower end the magazine portion 10 is formed with a downwardly tapering portion 12 from which project radial flange portions 14 which, as they continue downwardly, are reduced in width to form collar seats 15 and spring guide flanges 16. Continuing downwardly from the flanges 16, the width of the stave is still further reduced and it is arched transversely to form a lead guide portion 17 from which extend narrow radial flanges 18. The narrowed portions of the stave which are below the flanges 16 are also gripper arm portions, and they are given a set in an outwardly bowed form, as illustrated in the lower portion of Fig. 4, from which position they may be swung inwardly against their inherent resiliency. At a distance below the spring guide flanges 16 the narrow lateral flanges 18 are widened for a short distance to provide radially extending stop lugs 19, the flanges 18 terminating a short distance below said stop lugs, and the portions of the stave therebelow being formed as a narrow shank 20. The lower end portion of the shank 20 is swaged

to form a gripper jaw 21 having a serrated inner surface 22 which projects somewhat beyond the inner surfaces of the shank, and an outer wedging surface 24 which flares outwardly from the shank 20 and merges at its upper limit into a shoulder portion 25 which slopes outwardly from the shank 20 somewhat more abruptly.

A plurality of such stave members, three in the example illustrated, are assembled in complementary relationship so that their portions 10 and 11 cooperate to form a hollow receptacle which constitutes the magazine for the pencil, as illustrated in the cross-sectional view of Fig. 6. The flange portions 11 are of such width and extend at such angular relationship from the arched portion 10 that they meet those of the associated staves before the margins of the wider arched portions 10 meet each other and hence, when the three staves are pressed together, the flange portions 11 are placed under stress when the margins of the portions 10 are brought together, and in this tensioned condition the flanges 11 continue to tend to press the staves apart. The three staves are held in their assembled complementary relationship by a ferrule 26 and by a collar 27, the former being telescoped onto their upper ends, thus holding the flanges 11 in their tensioned condition, and the collar 27 being passed over the lower ends of the staves and onto the clamping flanges 15 thereof until it abuts the lower ends of the flanges 14. The ferrule 26 and collar 27 thus hold the margins of the stave portions 10 in contact with one another, and likewise the flanges 14 and 15 in engagement with one another, as illustrated in Fig. 7. Thus is formed a continuous tubular magazine with a conical bottom leading to a lead guide tube formed by the complementary arched portions 17 of the staves. When the staves are first placed in their complementary relationship and before they are bound together by the ferrule and collar, a filler cone 28 is positioned between their converging portions 12, thereby filling the conical bottom of the magazine, where it is retained in position by inwardly struck portions 29 of the staves. This filler cone 28 has its upper surface dished and it is formed with an axial bore 30 extending through it from top to bottom, which bore is of a size to pass a single lead stick at a time.

After being thus assembled, the slender gripper arm portions of the staves project in slightly divergent relationship below the lower end of the collar 27. A helical spring 31 is threaded onto them and its upper end portion is moved into encompassing relationship with the spring guide flanges 16 so that the upper end of the spring is engaged against the lower end of the collar 27 and the ends of the flanges 14. A washer 32 is then threaded onto the lower ends of the gripper arms which are pressed close to one another to permit their being inserted through a central aperture in the washer, which aperture is of size to receive the arched portions 17 of the arms loosely and has radially extending notches 34 arranged to pass the flanges 18 and stop lugs 19 of the three arms when those of juxtaposed arms are against one another. The washer 32 has also a lug 35 projecting radially from its margin in offset relationship to the notches 34. A guide bushing 36 is then threaded upon the lower end portions of the gripper arms. This bushing has an external shoulder 37 for seating upon a shoulder within the pencil barrel, and its lower end portion 38 is externally threaded for engagement with the pencil tip. The upper end of the bushing

is counterbored to receive the washer 32, and the bushing is provided with an axial bore which is stepped to provide an upper stop shoulder 39 and a lower stop shoulder 40, and for a distance from its upper end the wall of the bushing is provided with a longitudinal slot 41 extending radially through it to the bore. The upper portion of the bore, which is of the smallest diameter, is wide enough to receive the gripper arms loosely, including four of the lugs 19 when the remaining two adjacent lugs are inserted at the upper end of the slot 41. After the arms have been slid longitudinally through the restricted upper portions of the bushing bore to an extent such that the stop lugs 19 are brought to a position below the upper stop shoulder 39, the lugs 19 which were traveling in the slot 41 may be moved inwardly from the slot, and then the bushing may be rotated on the arms to position all of the lugs 19 below the shoulder 39. The washer 32 is rotated with the staves until its lug 35 is brought into alignment with the slot 41, whereupon the washer may seat in the counterbored upper end portion of the bushing. This engagement of the lug 35 in the slot 41 holds the washer 32 against rotation relative to the bushing 36, while the engagement of the flanges 18 in the notches 34 of the washer holds the assembled staves against rotating relative to the washer 32 and bushing 36. The spring 31 is compressed longitudinally to some extent incident to this assembly of the bushing 36 with the other parts, and it is retained in this partially compressed condition between the collar 27 and the washer 32, and the bushing 36 is retained against withdrawal from the gripper arms by the engagement of the stop lugs 19 against the upper stop shoulder 39, but the bushing may be slid upwardly along the gripper arms against the pressure of spring 31.

40 A clamping collar 42 is then threaded onto the lower ends of the gripper arms. This clamping collar is of external diameter such that it fits slidably in the enlarged lower portion of the bore of the bushing 36, whereby it is guided in coaxial relationship with the bushing. The clamping collar has an axial bore of diameter sufficient to accommodate the gripper shanks 40 when they are in their outward or divergent position, but upon retraction of the jaw portions 21 into the lower end of the clamping collar 42, said jaw portions 21 are wedged inwardly by the wedging action of the clamping collar upon the diverging shoulders 25 and the more gently flaring wedge surfaces 24. The stop shoulder 40 of the bushing provides an upper limit stop for the clamping collar 42 whereby it is held stationary to permit the retraction of the gripper jaws into its lower end, and, by the wedged engagement of the jaw surfaces 24 in the bore of the clamping collar, the latter is held so that it is moved forwardly in the bushing 37 by forward movement of the jaws.

45 In the ferrule 26 is secured a gauge member 44 which closes the upper end of the magazine excepting for a gauge opening 44a which is of width 60 to admit lead sticks of the maximum diameter that the pencil is designed to use, and a cap member 45 is removably mounted in the upper end of the ferrule 26 in such fashion that a portion of it is held projecting thereabove. This cap member 45 carries an eraser 46, and the cap member is reversible so that it may be mounted in the ferrule either in the position in which the eraser is housed in the latter, as shown, or in an inverted position wherein the eraser projects beyond the upper end of the ferrule.

The mechanism comprising the parts above mentioned may be completely assembled in the manner above described so that it may be inserted as a unit within the tubular barrel 41 of the pencil. This barrel is provided with an internal shoulder 48 upon which the shoulder 37 of the bushing 36 seats, the position of the shoulder 48 being such that the threaded end portion 38 of the bushing projects beyond the lower end of the barrel. The bushing 37 fits the bore of the barrel in such fashion that the bushing is maintained in coaxial position therein. The pencil tip 49 is screwed onto the end portion 38 of the bushing, the upper end of the tip abutting the lower end of the barrel and holding the bushing 36 fixedly mounted therein. The tip is formed with an internal shoulder 50 which forms a forward or lower limit stop for the slideable clamping collar 42, and has an axial bore which in its upper portion is of sufficient diameter to receive the jaws 21 when they are in divergent relationship beyond the lower end of the clamping collar. In the lower portion of the tip bore is mounted a lead retaining member 51 adapted to permit passage of a lead stick of the intended size, which retaining member has resilient portions adapted to grasp the lead stick so as to hold it frictionally against falling through the end orifice of the tip. With the pencil thus completely assembled, the mechanism is maintained in coaxial relationship with the barrel, the bushing 36 being retained in fixed position therein and the ferrule 38, magazine, lead guide tube, gripper arms and clamping collar 42 being reciprocable longitudinally in the barrel, the upper portion of the ferrule having guiding cooperation with the bore wall of the barrel as at 52. Accordingly, by holding the barrel stationary and pressing downwardly upon the projecting portion of the cap 45, the reciprocable parts may be moved downwardly or forwardly in the barrel against the pressure of spring 31, and upon release of the pressure on the cap, said parts will be returned upwardly or rearwardly to the limit position. When there is no lead stick between the jaws 21, the upper limit position is established by engagement of the stop lugs 19 against the shoulder 39, as shown in Fig. 1.

To load the pencil for operation, the cap member 45 is completely withdrawn and sticks of lead are charged into the magazine through the gauge opening 44a and the cap member is then put back in place. With the pencil held with its point downwardly, one of the lead sticks will pass from the magazine through the bore 30 of the filler cone 28 and into the lead guide portion 17 until it is brought to rest against the upper portions of the inwardly projecting gripping surface 22 of the jaws. The reciprocable portions of the mechanism then being pressed downwardly by pressure against the cap 45, the clamping collar 42 will be carried downwardly by the jaws until its lower end engages the stop shoulder 50, whereat its forward movement is arrested. The continued downward movement of the other portions, which is arrested only when the ends of the flanges 18 come into engagement with the upper end of the clamping collar 42, moves the jaws downwardly beyond the lower end of the clamping collar, thus freeing them of its constraint and permitting them to spring apart from one another and resulting in their being moved outwardly away from one another by the spring action of the gripper arms and shanks 20. This separation of the jaws permits the lead stick to fall on downwardly be-

tween them. When the pressure is removed from the cap 45, the reciprocable parts are returned upwardly by the spring 31, the jaws engaging the lower end of the clamping collar 42 and carrying it upwardly ahead of them, the jaws thus remaining in their open or cast off position and free of the lead stick until the upper end of the clamping collar is stopped against the shoulder 48 of the bushing 36, whereupon, with the continued upward movement of the magazine and jaws, the latter are wedged inwardly as they are drawn into the clamping collar, with the result that they are swung into gripping engagement with the lead stick. With the lead stick so gripped between the jaws, the upward movement of the parts is arrested before the stop lugs 19 reach the shoulder 39. The lead stick being thus held securely gripped by the jaws under the constraining action of the clamping collar 42, the reciprocable parts are again moved downwardly by pressure on the cap 45 and the lead stick is positively propelled downwardly and forced through the resilient retaining member 51. Thereafter, repeated operation of the reciprocable parts in the manner above described will be effective to feed the lead stick step by step, the length of feed at each operation being determined by the distance which the jaws move between their upper position of rest and the point at which they are freed from the constraining action of the clamping collar and permitted to move outwardly to disengage the lead stick. As the lowermost lead stick is thus fed forwardly step by step, a succeeding lead stick passes from the magazine and follows along by gravity until it reaches a position where it is engaged by the jaws. Thence it is fed forwardly step by step in the manner above described, propelling the short remaining portion of the preceding lead stick ahead of it. Accordingly, all of the lead sticks in the magazine may thus be fed successively to the writing point, step by step, by a series of successive operations of the reciprocable parts in the manner above described.

Among the advantages of this construction are the fact that the gripper arms are formed integrally with the magazine from flat stock which is of relatively low cost as compared with tubular stock. Moreover, the fabrication of those parts may be accomplished rapidly by pressing operation, thus eliminating relatively delicate operations such as are involved in the slitting of small tubes to form the gripping arms and jaws. Moreover, this stave construction provides a sheet metal lead guide tube in which the wall segments have slight inward and outward movement relative to one another, which has the effect of aiding the movement of the lead sticks by gravity, in that it reduces the likelihood of a stick's being stopped in the slender guide tube above the jaw shanks. This stave construction also reduces the likelihood of the slender guide tube becoming bent, because the individual segments of the tube, and hence the tube as a whole, are very effectively stiffened by the flanges 16 and 18. These several features are of definite advantage in obtaining certainty and reliability in the operation of the pencil, and another feature which contributes to the same end is the fact that tolerance variations which might affect the position of the jaws longitudinally in reference to the magazine and other associated parts are entirely eliminated. The stave construction also reduces the cost of making repairs

in event one of the jaws becomes damaged by misuse, as a new stave may be substituted for the one carrying the damaged jaw, thus permitting the pencil to be restored to operative condition without involving replacement of the other jaw and magazine portions.

What I claim is:

1. In a mechanical pencil, a lead feeding member comprising a plurality of staves having upper portions associated in complementary relationship to form a tubular magazine for lead sticks and lower portions associated in complementary relationship to form a lead guide tube of smaller diameter than said magazine and leading from the end thereof, said lower portions having parts at their lower ends shaped to provide lead-gripping jaws.

2. In a mechanical pencil, a lead feeding member comprising a plurality of staves having upper portions associated in complementary relationship to form a tubular magazine for lead sticks and lower portions associated in complementary relationship to form a lead guide tube of smaller diameter than said magazine and leading from the end thereof, said lower portions having parts at their lower ends shaped to provide lead-gripping jaws, and means retaining said upper portions of the staves in fixed association, said lower portions being susceptible of limited flexing movement toward and from one another.

3. In a mechanical pencil, a lead feeding member comprising a plurality of staves having upper portions associated in complementary relationship to form a tubular magazine for lead sticks and lower portions associated in complementary relationship to form a lead guide tube of smaller diameter than said magazine and leading from the end thereof, said lower portions having parts at their lower ends shaped to provide lead-gripping jaws, said lower portions having outwardly deflected parts extending longitudinally of them.

4. In a mechanical pencil, a lead feeding member comprising a plurality of staves having upper portions associated in complementary relationship to form a tubular magazine for lead sticks and lower portions associated in complementary relationship to form a lead guide tube of smaller diameter than said magazine and leading from the end thereof, said lower portions having parts at their lower ends shaped to provide lead-gripping jaws, said lower portions having outwardly deflected marginal flanges extending longitudinally of them.

5. In a mechanical pencil, a lead feeding member comprising a plurality of staves having upper portions associated in complementary relationship to form a tubular magazine for lead sticks and lower portions associated about a common axis to form a lead guide tube of smaller diameter than said magazine and leading from the end thereof, said lower portions having parts at their lower ends shaped to provide lead-gripping jaws, said lower portions being resilient and tending to spring outwardly from one another.

6. In a mechanical pencil, a lead feeding member comprising a plurality of staves having upper portions associated in complementary relationship to form a tubular magazine for lead sticks and lower portions associated in complementary relationship to form a lead guide tube of smaller diameter than said magazine and leading from the end thereof, said lower portions having parts at their lower ends shaped to form resilient outwardly-springing shanks carrying lead-gripping jaws.

7. In a mechanical pencil, a lead feeding member comprising a plurality of staves having upper portions associated in complementary relationship to form a tubular magazine for lead sticks and lower portions associated about a common axis to form a lead guide tube of smaller diameter than said magazine and leading from the end thereof, said lower portions having parts at their lower ends shaped to provide lead-gripping jaws.

5 8. In a mechanical pencil, a structure as specified in claim 1 and wherein said upper portions 10 are connected to said lower portions by downwardly tapering portions.

9. In a mechanical pencil, a lead feeding member comprising a plurality of staves having upper 20 portions associated in complementary relationship to form a tubular magazine for lead sticks and lower portions associated in complementary relationship to form a lead guide tube of smaller diameter than said magazine and leading from the end thereof, said lower portions having parts 25 at their lower ends shaped to provide lead-gripping jaws, a removable ferrule binding said staves together at their upper ends and a removable collar binding them together at the lower ends 30 of said upper portions.

10. In a mechanical pencil, a lead feeding member comprising a plurality of staves having upper portions associated in complementary relationship to form a tubular magazine for lead sticks 35 and lower portions associated in complementary relationship to form a lead guide tube of smaller diameter than said magazine and leading from the end thereof, said lower portions having parts at their lower ends shaped to provide lead-gripping jaws, a removable ferrule binding said staves together at their upper ends 40 and a cap member mounted on said ferrule and extending beyond its upper end, whereby pressure may be transmitted to the staves to move 45 them longitudinally as a unit.

11. In a mechanical pencil, a lead feeding member comprising a plurality of staves having upper portions associated in complementary relationship to form a tubular magazine for lead sticks 50 and lower portions associated in complementary relationship to form a lead guide tube of smaller diameter than said magazine and leading from the end thereof, said lower portions having parts at their lower ends shaped to provide lead-gripping jaws, juxtaposed staves having at their upper ends laterally deflected resilient parts in engagement with each other, and a ferrule binding said staves together with said resilient parts in stressed condition.

60 12. In a mechanical pencil, lead feeding mechanism including a plurality of resilient gripper arm portions arranged around a common axis and individually movable toward and from same, stop lugs extending outwardly from said gripper arm portions, a washer centrally apertured to permit passage of said gripper arm portions and their stop lugs and to retain it against rotation relative to them, a bushing having a bore with an inwardly jutting shoulder and a radial slot extending from one end to a point beyond said shoulder, said bore being formed to pass said gripper arm portions and stop lugs when certain 65 70 75 of the latter are positioned in said radial slot,

and means for retaining said washer in coaxial relationship with said bushing and against rotation relative thereto with said stop lugs in positions to engage said shoulder.

13. In a mechanical pencil, lead feeding mechanism comprising a bushing having an axial bore with an inwardly jutting shoulder and a lateral slot extending into the bore from one end of the bushing to a point beyond said shoulder, a plurality of gripper arm portions arranged around a common axis and having laterally projecting stop lugs, said gripper arm portions being movable longitudinally into said bore when certain of said lugs are in said lateral slot, and means for retaining said bushing against rotation relative to said gripper arm portions when said stop lugs are positioned in the bore and out of alignment with said slot.

14. In a mechanical pencil, a structure as specified in claim 13 and wherein said gripper arm portions are resiliently movable toward and from the common axis.

15. In a mechanical pencil, a structure as specified in claim 13 and wherein said gripper arm portions are resiliently movable toward and from the common axis, and means in the bushing for constraining said gripper arm portions toward said axis.

16. In a mechanical pencil, a structure as specified in claim 13 and including spring means effective on said gripper arm portions and said bushing to press said stop lugs toward said shoulder.

17. In a mechanical pencil having a magazine adapted to contain a plurality of lead sticks side by side, a lead guide tube leading from the magazine and having a bore of size to pass a single lead stick, said lead guide tube being formed of segments arranged around a common axis and having limited movement individually toward and from the same.

18. In a mechanical pencil, a lead feeding mechanism comprising a plurality of identical staves having complementary portions associated to form a magazine and other complementary portions associated to form a lead guide tube communicating with and of smaller diameter than said magazine.

19. In a mechanical pencil, a lead feeding mechanism comprising a plurality of identical arm members having arched portions associated to form a lead guide tube and radially extending portions cooperating with one another to position said arched portions in complementary relationship.

FRED P. MOORE.
